UNITED STATES PATENT OFFICE.

PETER KIMACK, OF ST. LOUIS, MISSOURI.

MOVABLE CENTER FROG.

1,318,768.

Specification of Letters Patent.

Patented Oct. 14, 1919.

Application filed July 19, 1919. Serial No. 311,929.

To all whom it may concern:

Be it known that I, PETER KIMACK, a citizen of the United States, and resident of St. Louis and State of Missouri, have invented certain new and useful Improvements in Movable Center Frogs, of which the following is a specification containing a full, clear, and exact description, references being had to accompanying drawings, forming a part thereof.

This invention relates to movable center frogs, and has for its primary object a center frog with movable points which are connected together by a lever mechanism, so that the opposing points will move in opposite directions simultaneously.

A further object is to construct a movable center frog which may be operated either from a tower, be hand thrown, or operate automatically by the passing of the wheels.

In the drawings,

Figure 1 is a plan view of my device as applied to a crossing.

Fig. 2 is a longitudinal sectional view of the same.

Fig. 3 is a top plan view of the lever mechanism made use of to throw the points.

Fig. 4 is a vertical cross section taken on the line 4-4 of Fig. 1.

Fig. 5 is a vertical cross section taken on the line 5-5 of Fig. 1.

Fig. 6 is a vertical cross section taken on the line 6-6 of Fig. 1.

Fig. 7 is a vertical cross section taken on the line 7-7 of Fig. 1.

Fig. 8 is a bottom plan view of the housing on which the frog points are mounted.

Fig. 9 is a perspective view of the yoke to which the head rods are secured.

Fig. 10 is a perspective view of the yoke to which the lock bars and back-throw rods are attached.

In the construction of my device I provide a housing 11, on which is integrally formed the running rails 12 and 13, the rail 12 extending the full length of the housing, and the rail 13 only partially from each end.

The running rails 13 are further provided with a socket 14 in which the end 15 of the frog point 16 is seated.

The frog point 16 is provided with an upwardly and rearwardly projecting flange or web 17, which is designed to come in contact with the flange of a car wheel.

The point 16 is provided at its rear end

with a pivot or stud 18, this pivot or stud being formed on the underside of the point.

The housing 11 is provided on its underside with a series of ribs 19, these ribs being perforated as indicated by the number 20.

The upper surface of the housing 11 is provided with an opening 21 which is formed directly above the opening 20 formed in the ribs 19 and through these two openings the pivot 18 is passed.

The housing 11 is also provided with slotted openings 22 through which studs 23 pass. These studs are formed integral with the bottom side of the points 16 and at a short distance from the free end thereof.

The center of the housing 11 is provided with an opening 24 which is directly over an opening 25 formed in the rib 26, which rib is also formed integral with the bottom of the housing. Through these openings the pin 27 is secured.

On this pin and under the top surface of the housing 11 is pivotally secured a lever 28, this lever being provided on both of its ends with a fork 29, which fork straddles the pin 23.

Immediately below this lever and secured to the pins 23 and 18 is the bar 30, this bar being provided on each of its ends with a perforation 31. To these perforations the locking bars 32 and the back throw rods 34 are secured.

Secured to the pin 23 and directly beneath the levers 30 are secured the head rods 35, and in order to keep the housing at the proper distance gage rods 36 are secured. These gage rods are of standard construction and therefore will not be described in detail as they are well known articles of commerce.

The head rods 35 are riveted in the depression 37 formed in the yoke 38 and opposite the depression 37 is formed a perforated ear 39, this ear being for the purpose of connecting the head rods directly to the switch stand, if so desired. Adjustably secured to the head rods are inter-locking bars 40, their connection is not shown as this is well-known to the art. The lock bar connection 32 is secured to the yoke 42. The connection also is provided with an extension or rod 41 which may be secured to the switch stand or target for operating the device.

The lock bars 32 are provided with a fork

44 and the nuts 44^a which are for the purpose of adjusting the points of the frogs. The rear end of the lever 30 is connected to an adjustable rod 45 which is provided with 5 a turn buckle 46 and is for the purpose of locking the frogs in adjusted position. In other words; when the fork 44 is adjusted and tightened the turn buckle 46 is drawn up thus holding the frog points in their 10 adjusted position.

The rearwardly projecting flange or web 17 is also provided with an oil hole 47, the purpose of which is to provide lubricant underneath the frog point. The frog point 15 and rearwardly projecting flanges or webs are provided with extensions 48, the purpose of which is to prevent any tilting tendency of the frog points when the wheels are passing over the same and the object of extending the flange rearwardly from the pivot point is to obviate a lifting tendency 20 of the frog point when the wheel first touches the rear of the frog.

That portion of the running rails which 25 are formed integral with the housing and is adjacent to the end thereof is provided with cut away portions 49 to which the track proper is secured. These cut away portions are to be formed on both ends of the housing.

30 If desired I may remove that portion of the lever 30 to which the back throw rods are attached as well as leaving out the back throw rods. This will cheapen the cost of construction and maintenance and still allow 35 the points to work and be adjusted, but where high speed traffic passes over a crossing, I find it advisable to also use the back throw rods.

When I desire to use my device automatically, that is to have the frog points 40 moved by the passage of the rolling stock, it is only necessary to use the connections shown between the two housings, as the points will be operated by the flanges of the 45 wheels coming in contact with the rearwardly extending flange 17.

This contact will throw the frog points in the desired position.

The rearwardly extending flanges or 50 wings 17, as will be observed, project rearwardly from the pivotal connection of the frog point and are formed integral therewith, and are spaced apart from the pivoted frog points proper and connected thereto by 55 a web 50, so as to provide a throat or passageway for the wheel flange see Figs. 1 and 6.

Having fully described my invention, what I claim is:

60 1. A movable center frog comprising a housing, running rails formed integral with the said housing and a pair of frog points pivotally mounted on said housing and forming a continuation of one of the run-

ning rails, a lever mechanism located beneath the housing for operating the frog points and a flange projecting rearwardly from the pivotal connection of the frog point and adapted to contact with the flanges of a railway wheel. 65

2. A movable center frog comprising a housing, a continuous running rail formed integral therewith and extending its entire length and a second running rail formed integral with the housing and extending only 70 a short distance from each end thereof, a frog point pivotally secured to the housing and abutting the ends of each short running rail, a lever mechanism mounted beneath the upper surface of the housing and connected 75 to the frog points, a rearwardly extending flange formed integral with each frog point adjacent the flange side of the frog point and extending beyond the pivot point thereof and projections formed on the rearward extending flange and on the frog point 80 for preventing side tilting of the same. 85

3. A movable center frog comprising a housing, a continuous running rail section formed on the top of said housing and extending throughout the entire length thereof, short running rail extensions carried by the housing, a pair of pivoted frog points pivotally secured to the housing, a lever connection between said pivoted frog points, 90 each of said pivoted frog points being provided with a rearwardly extending flange, said flange being formed integral with the frog points and connected thereto by means of a web and spaced apart from the frog points so as to form a passageway for the wheel flange, said rearwardly extending wings performing the function of a throw lever and a means for preventing the points 95 from lifting by the passage of the rolling stock. 100

4. A movable center frog comprising a pair of housings, means for connecting and holding said housings together, a pair of frog points mounted on each housing each 110 frog point being provided with a rearwardly extending wing, means for adjusting the free ends of the frog points to and from each other, and means for locking the free 115 ends of the points in the desired adjustment.

5. A movable center frog comprising a pair of housings, means for connecting and holding said housings together, a pair of frog points mounted on each housing each 120 frog point being provided with a rearwardly extending wing, means for adjusting the free ends of the frog points to and from each other, means for locking the free ends 125 of the points in the desired adjustment, and means for moving said frog points mechanically.

6. A movable center frog comprising a

pair of housings, means for connecting and holding said housings together, a pair of frog points pivotally mounted on each housing, a wing on each frog point to prevent 5 the same from laterally tilting, means for adjusting the free ends of the frog points to and from each other, means for locking the free ends of the points in the desired adjustment, a lever mechanism for connecting the respective parts of the frog points,

and means for moving said frog points mechanically.

In testimony whereof, I have signed my name to this specification, in the presence of two subscribing witnesses.

PETER KIMACK.
